UNITED STATES PATENT OFFICE.

PHILIP T. DODGE, OF WASHINGTON, DISTRICT OF COLUMBIA, ASSIGNOR
TO MERGENTHALER LINOTYPE COMPANY, A CORPORATION OF NEW
YORK.

LINOTYPE-MACHINE.

SPECIFICATION forming part of Letters Patent No. 761,289, dated May 31, 1904.

Application filed February 28, 1904. Serial No. 194,703. (No model.)

To all whom it may concern:

Be it known that I, PHILIP T. DODGE, of Washington, District of Columbia, have invented a new and useful Improvement in Linotype-Machines, of which the following is a specification.

The aim of my invention is to produce a machine in which speedy change may be effected from one font or set of matrices to another.

To this end it consists, essentially, in the combination of a distributing mechanism and assembling mechanism with an intermediate frame carrying a plurality of magazines, either of which may be removed independently and replaced by another.

The machine is susceptible of many modifications in detail; but I have illustrated herein a construction which will answer a good commercial purpose.

The details of the distributing mechanism and the casting mechanism may be of any ordinary construction. In the drawings I have indicated a distributor of the ordinary Mergenthaler type.

Figure 1 is a front elevation of the leading parts of a machine on my plan. Fig. 2 is a side elevation of the same. Fig. 3 is an enlarged sectional view through the base of one of the magazines. Fig. 4 is a similar view of a modification.

Referring to the drawings, A represents the main frame, and B a skeleton frame or support for the magazines mounted to slide forward and backward on guide-rails b at its foot or otherwise supported in any suitable manner, so that it may be moved. C C', &c., represent a series of vertical channeled magazines mounted in this movable frame. They are inserted horizontally from one side and are arranged so that either one may be withdrawn independently of the others and replaced by a magazine carrying a different font of matrices. These magazines may be of any suitable construction. They are preferably made, as in the ordinary Mergenthaler machines, of two parallel plates rigidly connected, their inner faces being separated and grooved vertically to receive and guide the

edges of the matrices, which stand in vertical rows therein, entering at the top from the distributor and leaving at the foot to pass to the assembling or composing devices. In the present instance the distributor consists, as in the Mergenthaler machine, of a horizontal fixed bar D, overlying the magazines and having its lower edge of V form provided with longitudinal teeth permuted in arrangement for the purpose of engaging teeth in the upper notched ends of the matrices and sustaining them as they are carried along the bar until they arrive over the appropriate channels in the magazine.

E represent the usual horizontal screws lying adjacent to the distributor-bar for the purpose of carrying the matrices along the same. The usual or other suitable devices will be employed to lift the matrices from the casting mechanism and deliver them one at a time to the distributor-bar and feed-screws. The matrices falling from the distributor pass directly into the upper end of the magazine thereunder, and by moving the magazine-frame B forward and backward one of the contained magazines may be brought below and in operative relation to the distributor. In other words, the one distributor is caused to deliver matrices into either of the several magazines by changing their relations.

F represents the throat or raceway fixed in the main frame and located beneath the magazine in position to receive matrices from the lower end of that magazine which is at the time in position to receive matrices from the distributor. This raceway consists of vertical plates and intermediate partitions, which guide the matrices downward toward contracted lower end or mouth of the race-plate, through which the matrices pass in succession one at a time. Traveling belts G may be used at the side to facilitate the downward travel of the matrices.

H represents the keyboard containing a series of finger-keys, from which vertical rods or reeds I are extended upward to the escapements J of that magazine which is for the moment in position. These rods act on the es-

capements and throw them in one direction, and when the rods are released the spring K returns them to their original positions. Each magazine is provided with its own set 5 of escapements. They should be covered or shielded, so that there will be no danger of their being injured when withdrawn from the frame. If preferred, a single set of escapements may be mounted in the frame at the 10 upper end of the throat or raceway and kept in connection with the operating-rods I, as shown in Fig. 4. In such case the matrices will be held in those magazines which are not in action by the fixed underlying plate M, 15 which is slotted over the escapements and the raceway, but not elsewhere. This plate will sustain the matrices in those magazines which are not in action. I propose also to provide in some cases other means of holding the 20 matrices within the magazines—such, for example, as a rod thrust through the lower end of the magazine, in the manner illustrated in my United States Patent No. 548,432.

In order to permit an easy movement of the 25 frame B, I propose to employ ball-bearings, as shown in the drawings, consisting simply of a series of balls interposed between the frames and the supporting rails or guides; but it is to be understood that this is not an 30 essential feature of my construction.

What I claim is—

1. In a typographic machine, the combination of a main frame, a second frame movable therein, to bring different magazines to the 35 operative position, and a plurality of parallel independently-removable magazines seated in said second frame, substantially as shown and described, whereby change from one font or face to another, may be effected by shifting the 40 secondary frame without changing the relation of the contained magazines to each other.

2. In combination with a fixed distributer, a relatively movable frame and a series of independently - removable magazines in said frame. 45

3. In a typographic machine, in combination with a supporting-frame, a series of upright magazines adapted to be inserted and withdrawn horizontally in an endwise direction. 50

4. In combination with a fixed raceway or throat, a frame movable thereover, and a series of independently-removable magazines in said frame. 55

5. In a typographic machine, a series of upright magazines laterally movable to bring one or another to an operative position, said magazines removable independently in a horizontal direction. 60

6. In a typographic machine, a main frame and an assembling mechanism therein, in combination with a series of upright matrix-magazines, independently removable in an endwise direction, and a magazine-support movable in the main frame transversely of the magazines, 65 to bring one or another into operative position. 65

7. In a typographic machine, the combination of a fixed distributer, a fixed assembling mechanism, an intermediate movable frame, 70 and a series of matrix-magazines carried by the movable frame and individually removable therefrom, whereby one magazine may be continued in action while the others are being changed. 75

In testimony whereof I hereunto set my hand, this 27th day of January, 1904, in the presence of two attesting witnesses.

PHILIP T. DODGE.
